MAGAZINE MOUNTING AND ADJUSTMENT

Filed June 21, 1928

UNITED STATES PATENT OFFICE

LOUIS H. LARSEN, OF UNION CITY, NEW JERSEY, AND CLIFTON W. NIXON, OF NEW YORK, N. Y.

MAGAZINE MOUNTING AND ADJUSTMENT

Application filed June 21, 1928, Serial No. 287,297, and in Great Britain July 13, 1927.

This invention relates to a magazine mounting and adjustment and is illustrated as embodied in a combined vending and change making machine having a rotary magazine adapted to carry a series of merchandise holding units and a series of change holding units.

The primary object of the invention is the provision of an improved magazine mounting which shall have improved means whereby readily and minutely to adjust the position of the magazine.

Another object of the invention is to provide a mounting and adjustment of the type referred to and in a manner as hereinafter set forth which will keep a rotary vertically disposed magazine in a state of equipoise irrespective of its load, whether light or heavy, one which will prevent the magazine from being whirled or rotated too rapidly when its load is light, and one which will, nevertheless, permit the magazine to be rotated with ease when its load is heavy.

Further objects of the invention are to provide a mounting of the type referred to and in a manner hereinafter set forth which is simple in its construction and arrangement, strong, durable, thoroughly efficient in use, as well as providing an adjustment of the type referred to whereby with ease and accuracy the magazine can, while loaded, be elevated or lowered so that parts supported thereby may be brought into proper relation with cooperating parts supported independently thereof.

Other objects will appear hereinafter.

The invention consists in the details of construction and in the arrangement and combination of parts hereinafter described and claimed.

The invention will be best understood by reference to the accompanying drawings forming a part of this specification, and in which:

Fig. 1 represents a fragmentary sectional elevation of a combined vending and change making machine constructed in accordance with and embodying the invention;

Fig. 2 represents a partial sectional elevation on a larger scale, showing the axial

mounting and adjustment structure for the magazine;

Fig. 3 represents a plan and section, taken substantially on the line 3—3 of Fig. 1, showing a portion of the magazine with a coin holding unit which is to be brought into operative relation in respect of the means for ejecting the coins; and

Fig. 4 represents a fragmentary sectional detail, showing a modified construction which may be adapted for securing the pedestal foot to the casing base.

The combined vending and change-making machine, illustrated in the accompanying drawings and in which we have shown an embodiment of our invention as a preferred example, comprises a casing 10 mounted upon a rigid base 11 and divided interiorly by a flexible section or diaphragm 12 into a compartment 13 adapted to contain a supply of merchandise and a compartment 14 in which are located a rotary vertically disposed magazine structure and other working parts of the machine.

The magazine structure, indicated generally by the numeral 15, is of skeleton form comprising a circular lower section 16 and a circular upper section 17, said sections being rigidly connected by rods 18. Fixed to the lower section 16 is a ring plate 18' on which are mounted a circular series of upright holding units 19 for containing the merchandise to be sold; and fixed to the upper section 17 is a ring plate 20 carrying a corresponding circular series of change-holding units 21, each composed of a plurality of wells 22 for containing the change to accompany the merchandise to be sold. The ring plate 20 has secured thereto an internal gear 23 with which is engaged a driving pinion 24 operated through shaft 25, bevel gears 26, stud shaft 27 and sliding connections 28, from an operating handle 29 arranged for rotation in a bearing block 30. Through the rotation of the handle 29, the magazine structure can be turned so as to bring any desired merchandise holding unit 19 with its accompanying change-holding unit 21 into delivery position with relation to the delivery receptacle 31.

In the present instance, the machine is represented as being provided with three bell crank actuators 32, 33 and 34 (Fig. 3) mounted to command, when operated, the respective coin ejectors 32', 33' and 34' adapted to enter suitable rear openings 35 in the wells 22 so as to eject coins through the front or delivery openings 36 thereof. Each of the bell crank actuators 32, 33 and 34 commands, when actuated, a lift frame 37, lift sleeve 38, lift shaft 39 which is pinned to said sleeve at 40, ball and socket joint 41, rod 42, and bell crank 43 for imparting a pushing stroke to the master pusher 44. Each merchandise holding unit 19 is furnished with a merchandise ejector 45, and when a holding unit is brought into delivery position behind the delivery receptacle 31, its ejector 45 is alined with the master pusher 44 to be operated thereby on the pushing stroke thereof for the discharge of merchandise into said delivery receptacle. With the parts arranged as described, it is possible to effect the discharge of change and merchandise on the operation of each of the bell crank actuators.

The bearing block 30 is supported solely by a fulcrum pin 46 on the frame 47 so that the handle 29 can be moved downwardly or depressed with the bearing block turning on the fulcrum pin 46 for the purpose of providing power for advancing inwardly of the casing away from the front wall 48 thereof a carrier structure 49, this operation being accomplished through the medium of a train of parts comprising a bell crank 50, link 51, and pull bar 52 adapted to be engaged with a draw bar 53 which is pivotally attached to said carrier structure. For each bell crank actuator, there is provided on the carrier structure a coin-controlled unit 54 commanding a hooked draw bar 55 adapted, when the carrier structure is advanced to extreme position from the front wall 48, to be interengaged with its corresponding bell crank actuator so as to operate the same and effect a discharge of merchandise and change as the carrier structure is returned toward the front 48 to its initial position. During the return stroke of the carrier structure, a kick-up pin 56 resting on the sleeve 38 and there-with elevated impinges the draw bar 53 and disconnects the same from the pull bar 52. For a full description and disclosure of the carrier structure and of the coin-controlled units supported thereby, reference may be had to an application filed by Clifton W. Nixon on June 7, 1927, Serial No. 197,075.

Our invention, in its preferred forms of construction as illustrated in the accompanying drawings, comprises a pair of adjustably connected co-axial shafts vertically arranged for supporting the magazine structure upon the rigid base 11, one of the shafts consisting of a pedestal shaft 57 which is placed upon the rigid base 11, and the other of the shafts

consisting of an axis shaft 58 on which the magazine structure is supported for free rotation. The pedestal shaft 57 may be made with an annular foot flange 59 adapted, as shown in Figs. 1 and 2, to rest flat upon the rigid base 11, and said shaft may be operatively secured to said base by means of a screw bolt 60 which extends upwardly through said base and is screw-threaded into said shaft. With this simple construction, it is possible quickly to loosen the screw bolt and turn the pedestal shaft by inserting a rod, pin or other suitable implement in one of the apertures 61 provided therein for the purpose, the loosened screw bolt turning with said shaft and serving as an axis boss for the same during the turning operation. By tightening the screw bolt the pedestal shaft can be secured rigidly with the base.

At its upper end the pedestal shaft is provided with a head 62 having therein a screw-threaded bore or recess 63 in which is engaged the screw-threaded end portion 64 of the axis shaft 58. A suitable opening 65 in the flexible diaphragm 12 provides for the passage therethrough of the axis shaft, this opening in the present instance being in or near the center of the diaphragm as the two co-axial shafts 57 and 58 are located substantially in the center of the casing. Threaded upon the screw-threaded portion 64 are two binding nuts 66 and 67. The binding nut 66 has for its object the provision of means for securing the shafts 57 and 58 together when it is turned down tightly against the end of the head 62 as shown in Fig. 2.

The upper or plain portion of the axis shaft 58 has turning fit in an opening or bearing 68 provided centrally in the lower section 16 of the magazine structure; and ball race sections 69 and 70 with intervening balls 71 are provided in a seat 72 in the lower portion of section 16 as means for supporting the magazine structure for free rotation upon the axis shaft, the ball race section 70 being suitably arranged upon a collar 73 secured by a pin 74 to the axis shaft. Depending from the collar 73 are pins 75 which engage pilot openings 76 in the diaphragm 12. One purpose of the co-operating pins and pilot openings is to insure that the master pusher 44, which is supported upon the axis shaft 58, will be properly alined in respect of the delivery receptacle 31 and in respect of the merchandise holding units when they are in delivery relation thereto, so that the ejectors 45, when operated by the master pusher, will efficiently discharge the merchandise into the receptacle 31. The pilot openings also provide for rapid and accurate assembly of the construction by unskilled workmen. In conjunction with the pins 75 engaging in the pilot openings, the binding nut 67, when turned tightly against the underside of the diaphragm, provides means

for securing the axis shaft against turning movement while permitting it to have endwise movement in connection with the flexing upwardly or downwardly of the diaphragm. If desired, a rigid element having pilot openings therein may be employed as a substitute for the flexible diaphragm, in which event the pins 75 must have a length sufficient to allow for the range of adjustment desired and suitable washers or equivalent devices may be provided in order to obtain the requisite binding action in connection with the collar 73 and binding nut 67.

As illustrated in Fig. 1, the axis shaft 58 terminates at 77 a short distance above the master pusher; and the upper portion of the magazine structure is operatively held in place by a shaft 78 fast with the upper section 17 to turn therewith. The shaft 78 may be operatively held in place in any convenient manner, as by a frame part 79. It has the lift sleeve 38 sliding thereon, the lift shaft 39 telescoping therein, and the pin 40 which connects said lift sleeve with said lift shaft works in a longitudinally extending slot 80 therein. Further, for maintaining the rotary magazine structure in a proper state of equipoise, for effectually arresting and positioning it when a holding unit is in delivery position, as well as to prevent it from being rotated too rapidly by the operating handle 29, the upper ring plate 20 has its outer circumferential edge 81 provided with spaced circular indentures 82 and with inwardly sloping edges 83 leading to said indentures as illustrated in Fig. 3, and suitable spring-cushioned rollers 84 are suitably supported on the casing for turning on the circumferential edge 81 and both into and out of the indentures 82 by way of the sloping edges 83. In the present instance, we illustrate in Fig. 1 two rollers 84 arranged in diametrically opposite relation to have concerted action on the ring plate so that if the magazine structure be turned a little too far, bringing a holding unit beyond its delivery position, the rollers will cause it to turn back until they seat in the indentures 82, and if the magazine structure be stopped a little short of proper delivery position for a selected unit, then the rollers will continue the advance until they have become seated in the indentures. The operative faces of the rollers 84 and of the driving pinion 24 are preferably of sufficient extent vertically to allow for the vertical adjustment of the magazine structure.

To adjust the magazine structure vertically so that the coin ejectors 32', 33' and 34' can enter the rear openings 35 and discharge the lowermost coins in the wells 22 through the front or delivery openings 36, the screw bolt 60 and the binding nut 66 are loosened. The pedestal shaft is then turned causing the axis shaft and magazine structure supported thereby to be elevated or lowered as desired,

it being understood that by turning said pedestal shaft in one direction, for instance to the right, the axis shaft will be elevated, while by turning it in the opposite direction, for instance to the left, the axis shaft 70 will be lowered.

In Fig. 4, we illustrate a modification in the construction for operatively attaching the pedestal shaft 57 to the base 11. According to this modification, a plug 85 is screw-threaded into the base 11 and protrudes thereabove. The pedestal shaft rests upon the plug, and a binding nut 86 having an inturned flange 87 engaging over the foot flange 59 of the pedestal shaft is screw-threaded upon the plug. By loosening the binding nut, the pedestal shaft may be turned upon the plug; and by tightening the binding nut the pedestal shaft will be secured in position against accidental turning.

The arrangement shown and described is very simple in construction, inexpensive to manufacture and easy to assemble. It is designed so as to afford a firm and staunch mounting, capable of ready and fine adjustment, and one which is not liable to become disconnected or get out of order.

It will be apparent from what has been said that we have produced a novel and useful construction of mounting and adjustment which embodies the features of advantage enumerated in the statement of invention and the above description, and while we have, in the present instance, shown and described a specific form of mechanism embodying the principle of our invention, it is to be understood that this is susceptible of modification in various particulars without departing from the spirit and scope of our invention or sacrificing any of its advantages.

Having thus described our invention, what we claim is:

1. A mounting and adjustment comprising in combination with a casing and magazine, a pair of co-axial uprights supporting said magazine within said casing, the upper upright constituting an axis for the rotation of said magazine thereon and supported by said lower upright for bodily endwise adjustment, and means securing the upper upright against rotation while permitting endwise adjustment thereof.

2. A mounting and adjustment comprising in combination with a casing and a magazine therein, an axis shaft and a pedestal shaft held together by a screw-threaded connection, said axis shaft constituting the support for said magazine, said pedestal shaft constituting the support for said axis shaft, and a centering connection between the base of the casing and said pedestal shaft.

3. A mounting and adjustment comprising in combination with a casing and a magazine therein, an axis shaft and a pedestal shaft

held together by a screw-threaded connection and supporting the magazine upon the base of the casing, the magazine being rotatably mounted on said axis shaft, a centering connection between the casing base and pedestal shaft permitting the latter to be turned, and means in connection with the casing and said axis shaft preventing rotary movement of said axis shaft while permitting endwise movement thereof.

4. In a machine of the kind described, consisting of a casing and a magazine, a pedestal shaft arranged on the base of the casing for turning movement, an axis shaft supported by the pedestal shaft and connected therewith to receive movement therefrom, anti-friction means on said axis shaft supporting the magazine thereon for free rotation, and interengaging parts on said casing and said axis shaft arranged to prevent the turning of said axis shaft while permitting endwise movement thereof by the turning movement of said pedestal shaft.

5. In a machine of the kind described, consisting of a casing and a magazine, a pedestal shaft arranged on the base of the casing, an axis shaft screw-threaded to said pedestal shaft, a ball-bearing structure on said axis shaft supporting the magazine thereon for free rotation, a flexible diaphragm on the casing receiving said axis shaft, and means securing said axis shaft to said diaphragm to prevent rotation of said axis shaft while permitting limited endwise movement thereof.

6. In a machine of the kind described, consisting of a casing and a magazine, a pedestal shaft arranged on the base of the casing, an axis shaft screw-threaded to said pedestal shaft, a ball-bearing structure on said axis shaft supporting the magazine thereon for free rotation, a flexible diaphragm on the casing, means securing said axis shaft to said diaphragm to prevent rotation of said axis shaft while permitting limited endwise movement thereof, and means for securing said axis shaft rigid with said pedestal shaft.

7. In a machine of the kind described, consisting of a casing and a magazine, a pedestal shaft on the base of the casing adapted to receive a turning implement, an axis shaft screw-threaded to said pedestal shaft, a ball-bearing structure on said axis shaft supporting the magazine thereon for free rotation, parts on the casing and on said axis shaft cooperating to prevent the rotation of said axis shaft while permitting endwise adjustment thereof, and centering means retaining said pedestal shaft in place on the base.

8. In a magazine mounting and adjustment, the combination with a casing having a diaphragm and a rigid base, of an axis shaft supporting a magazine and extending through said diaphragm, means on said axis shaft cooperating with said diaphragm to

prevent rotation of said axis shaft while permitting endwise movement thereof, a pedestal shaft screw-threaded to said axis shaft and supporting said axis shaft and magazine thereon upon said rigid base, said pedestal shaft being mounted on said base for turning movement and controlling the endwise movement of said axis shaft and magazine thereon.

9. In a magazine mounting and adjustment, the combination with a magazine supported on a vertical non-rotatable longitudinally movable axis shaft, of a rotary coaxial pedestal shaft arranged to support said axis shaft and adapted, when given rotary movement, to cause the axis shaft to move longitudinally and thus to adjust the elevation of the magazine.

10. In a machine of the kind described, the combination with a casing and a magazine therein supported on a vertical non-rotatable longitudinally movable axis shaft, of a pedestal shaft comprising the support for said axis shaft and therewith connected for controlling the longitudinal movement thereof, a ring on the magazine, and roller devices supported on the casing and arranged to turn on said ring.

11. In a machine of the kind described, the combination with a casing containing movable ejectors and a magazine having openings therein adapted to receive said ejectors, of a vertical non-rotatable longitudinally movable axis shaft, ball-bearing structure on said shaft supporting said magazine thereon for rotation, and a pedestal shaft supporting said axis shaft and therewith connected for controlling the longitudinal movement thereof, to adjust said magazine to a place where the openings therein will be accurately-positioned to receive said ejectors.

12. In a machine of the kind described, the combination with a casing containing operable parts and a magazine having parts adapted to cooperate with said operable parts, of a vertical non-rotatable longitudinally movable axis shaft supporting said magazine for rotation, a pedestal shaft supporting said axis shaft and therewith connected for controlling the longitudinal movement thereof so as to adjust the magazine and keep the parts thereof in operative relation to the cooperating parts on the casing.

13. In a machine of the kind described, the combination with a casing containing operable parts and a rotary magazine having parts adapted to cooperate with said operable parts, of a vertical non-rotatable longitudinally movable axis shaft supporting said magazine for rotation, a pedestal shaft supporting said axis shaft and therewith screw-threaded for controlling the longitudinal movement thereof so as to adjust the magazine and keep the parts thereof in operative relation to the cooperating parts on

the casing, and a nut associated with said screw-threaded connection for binding said axis shaft and pedestal shaft together.

In testimony whereof, we have signed our names to this specification.
